UNITED STATES PATENT OFFICE.

CORNELIUS S. VAN WAGONER, OF BROOKLYN, NEW YORK, ASSIGNOR TO
THE VAN WAGONER & WILLIAMS COMPANY, OF JERSEY CITY, NEW
JERSEY.

SPRING-HINGE.

SPECIFICATION forming part of Letters Patent No. 500,086, dated June 20, 1893.

Application filed January 2, 1889. Serial No. 295,123. (No model.)

To all whom it may concern:

Be it known that I, CORNELIUS S. VAN WAGONER, of Brooklyn, in the county of Kings and State of New York, have invented 5
certain new and useful Improvements in Spring-Hinges; and I do hereby declare that the following specification, taken in connection with the drawings furnished and forming a part of the same, is a clear, true, and 10
complete description of said improvements.

My improvements relate to that class of spring hinges which are so organized, that they not only serve to close a door, and to maintain it in its closed position, but also 15
serve to throw the door fully backward, and to hold it there.

The object of my invention is to secure said well known mode of operation, in a desirably effective way, by means which are 20
extremely simple and inexpensive, as compared with those employed in any prior hinge of this general class of which I have cognizance.

In my hinge, I employ leaves which are or 25
may be substantially as heretofore, in all respects relating to their general form, and the arrangement of their laterally projecting ears, and the pintles which connect them. The leaves of my hinges, have also at their inner 30
or coincident edges, inwardly projecting loops, to which I apply an elastic band spring which is preferably double, (like a section of rubber tubing,) and said loops may be cut through at one end, so as to receive the band spring, 35
or one or both of them may be solid, so that the spring may be coupled therewith by means of pins. A hinge with a spring thus constructed and applied, has a very wide range of movement, between its closed position, and 40
that so called "dead point" at which a door will stand fully opened and uninfluenced by the spring, but having passed said point, the spring will promptly throw the door backward, and hold it there.

45 To more particularly describe my invention, I will refer to the accompanying drawings in which—

Figure 1, is a front view of one of my hinges in its closed position. Fig. 2, illustrates the 50
same in its opened or thrown back position,

but in central cross section. Fig. 3, illustrates the band spring in side view, and cross section. Fig. 4, illustrates in cross section, one of my hinges, and a band spring applied thereto by means of pins. Fig. 5, illustrates 55
in front view, a hinge with the spring applied as in Fig. 4. Fig. 6, illustrates the "dead point" position of one of my hinges, and shows the wide range of movement, as by a door in swinging from its closed position to said 60
"dead point."

The hinge leaves A, and outwardly projecting ears a, are separately pivoted in pairs as heretofore. The loops b at the inner edges of the leaves, when designed for duty as in 65
Figs. 4 and 5, are precisely as heretofore used by me in hinges embodying spiral springs located longitudinally between the ears, but when used as in Figs. 1 and 2, said loops are slotted or cut at one end, as at b', so that said 70
loops are in fact, hooks.

The band spring B, is preferably composed of fine rubber, preferably in the form of a flattened tube, which can be conveniently applied in either of two ways here shown, and 75
in either case, it can be relied upon for substantial service for inside duty, and also for one or more ordinary summer seasons when exposed to the weather, as on outside screen doors. When applied as in the hinges shown 80
in Figs. 1 and 2, it is only necessary to slip the spring, under tension, into the two loops or hooks b, through the slots b', but with the true loops b, of the hinge Figs. 4 and 5, the 85
spring is applied, by passing flattened or folded portions of the spring through the loops, and then inserting the pins c, through the folds of the spring, so that the latter at 90
their two ends will have a firm bearing at the ends of the loops, and securely retain the 95
spring in place, as clearly indicated. It will be readily seen that with the band spring thus applied back of the hinge line, or hinge pivots it will hold the leaves in either of their extreme positions, and that a door can be swung upward of one hundred and thirty degrees from its closed position, before reaching the point, beyond which it must swing, before the spring will act to throw the door backward, as indicated in Fig. 6.

I am aware that it is not new to employ a retractile spiral spring applied crosswise of the leaves of a hinge, and arranged to perform the double duty common to this general 5 class of hinges, and hence it is to be understood that my invention is not only restricted to a band spring, but also to its direct application to the inner edges of the leaves, whereby I obtain, in what I believe to be, its simplest and most inexpensive form, a spring hinge, having as wide a range of movement 10 between its closed position and the "dead point," as is possible in any of the more complex and comparatively expensive forms of 15 spring hinges.

Having thus described my invention, I claim

as new and desire to secure by Letters Patent—

The combination of a pair of hinge leaves provided with separately pivoted pairs of 20 projecting ears, and loops or hooks at the inner edges of the leaves, and a band spring back of the pivot line and secured under tension to both of said hooks, and adapted to exercise its force in holding the leaves of the 25 hinge in either of their extremes in position, due to their movement on their pivotal connections.

CORNELIUS S. VAN WAGONER.
